US00D731519S

(12) **United States Design Patent**
Walsh et al.

(10) **Patent No.:** **US D731,519 S**
(45) **Date of Patent:** **** Jun. 9, 2015**

(54) **CONTEXT-ADAPTIVE USER INTERFACE
FOR A PORTION OF A DISPLAY SCREEN**

(71) Applicant: **Adobe Systems Incorporated**, San Jose, CA (US)

(72) Inventors: **Daniel Walsh**, San Francisco, CA (US); **Liang-Cheng Lin**, Milpitas, CA (US); **Philip Brian Dils**, San Francisco, CA (US)

(73) Assignee: **Adobe Systems Incorporated**, San Jose, CA (US)

(**) Term: **14 Years**

(21) Appl. No.: **29/444,835**

(22) Filed: **Feb. 4, 2013**
